UNITED STATES PATENT OFFICE.

WILLIAM HALL, OF MARION, OREGON.

LOCK FOR MILK-CAN LIDS.

No. 853,406.

Specification of Letters Patent.

Patented May 14, 1907.

Application filed August 4, 1906. Serial No. 329,210.

To all whom it may concern:

Be it known that I, WILLIAM HALL, a citizen of the United States, residing at Marion, in the county of Marion and State of Oregon, 5 have invented new and useful Improvements in Locks for Milk-Can Lids, of which the following is a specification.

This invention is a lock for milk-can lids or stoppers, and has for its object to provide a simple, cheap and efficient device of this kind which can be readily applied to any ordinary milk-can, and which can be easily operated.

In the accompanying drawing Figure 1 is 15 an elevation of the invention showing the application thereof. Fig. 2 is a vertical section on the line 2—2 of Fig. 1. Fig. 3 is an elevation showing the invention in unlocked position. Fig. 4 is an elevation showing the 20 manner in which the lid or stopper is supported when removed from the can.

Referring specifically to the drawing, 10 denotes a milk-can; and 11, the neck thereof which receives the lid or stopper 12 at a close fit. The neck is flared at 13 as usual, and the 25 lid is shaped accordingly.

The neck and lid have openings 14 and 15 which, when brought into registering position receive a bolt 16 having at one end a head 17, and at the other end a transverse 30 opening 18 to receive the locking device to be hereinafter described.

The locking device comprises a single piece of wire which is extended through the opening 18, and is doubled or bent as at 19 to form 35 two substantially parallel members 20 and 21, respectively, which are bent into the angular shape shown. The free ends of the members 20 and 21 are bent into eyes 22 40 which receive a ring 23.

In locking position, the member 20 extends transversely through the opening 18 in the bolt, and on opposite sides thereof on the outside of the can-neck. With the wire in 45 this position the bolt cannot be withdrawn from the openings 14 and 15, and the lid is therefore securely locked to the can-neck. To remove the lid, the member 20 is slid forwardly through the opening 18 until the part 50 19 extends therethrough. The wire can

then be turned to bring it in alinement with the bolt which can then be withdrawn from the openings to release the lid and permit its removal from the can. The wire will also be drawn through the openings, and the lid can 55 be suspended therefrom to hang on the outside of the can as shown in Fig. 4. The openings are large enough to take the wire, and it is prevented from being withdrawn therefrom by the ring 23. The wire also affords 60 convenient means for supporting a shipping tag 24 as shown.

The device herein described can be readily applied to any ordinary milk-can, and it is simple in construction and can therefore be 65 cheaply produced. It can be easily operated, and effectively serves the purpose for which it is intended.

I claim:

1. The combination with a can and its lid, 70 said lid and the neck of the can having registering openings, of a bolt extending through the openings, and having at one end a transverse opening, and a locking device comprising a piece of wire which is doubled to form 75 two substantially parallel members, one of which extends through the opening in the bolt and on opposite sides thereof, and is extensible into axial alinement with the bolt to permit its withdrawal.

2. The combination with a can and its lid, 80 said lid and the neck of the can having registering openings, of a bolt extending through the openings, and having at one end a transverse opening, and a locking device comprising a piece of wire which is doubled to form 85 two substantially parallel members, one of which extends through the opening in the bolt, and is extensible into axial alinement therewith to permit its withdrawal, and a retaining member on the free ends of the aforesaid members.

In testimony whereof I have signed my name to this specification in the presence of two subscribing witnesses.

WILLIAM HALL.
